UNITED STATES PATENT OFFICE.

JOSEPH MATALONI, OF MASON CITY, IOWA.

PADLOCK.

Application filed October 22, 1924. Serial No. 745,072.

To all whom it may concern:

Be it known that I, JOSEPH MATALONI, a subject of the King of Italy, residing at Mason City, in the county of Cerro Gordo and State of Iowa, have invented certain new and useful Improvements in Padlocks, of which the following is a specification.

This invention relates to key-actuated locks, being here shown as embodied in a padlock, the invention having for an object to provide a novel form of key-actuated padlock in which the key is retained in the lock when the latter is open. A further object of the invention is to provide a novel form of lock in which the movable locking element has fixed thereto a number of plunger pins that are controlled in their movement by the key.

For further comprehension of the invention, and of the objects and advantages thereof, reference will be had to the following description and accompanying drawing, and to the appended claims in which the various novel features of the invention are more particularly set forth.

Fig. 1 of the drawing is a longitudinal sectional view of a padlock constructed according to my invention, the lock being open, this view being taken generally on the line 1—1 of Fig. 2.

Fig. 2 is a longitudinal sectional view at right angles to Fig. 1 and taken on the line 2—2 of the latter figure.

Fig. 3 is a transverse sectional view taken on the line 3—3 of Fig. 1.

Fig. 4 is a like view to Fig. 1 but showing the lock as closed.

Fig. 5 is a transverse sectional view taken on the line 5—5 of Fig. 4.

Fig. 6 is a like view to Figs. 1 and 4, showing the parts in still another position.

Fig. 7 is a horizontal sectional view taken on the line 7—7 of Fig. 6.

Fig. 8 is a face view of the key.

As here embodied my improved padlock comprises a casing 10 which may be of common rectangular shape and which is provided with a pair of apertures 11 and 12 in one end to receive respectively the shank and beak of the shackle 13. The shank of the shackle extends longitudinally within the casing, adjacent one of the side walls thereof, and passes longitudinally through one arm of an L-shaped block 14 slidable longitudinally of the casing the other arm of this block extending transversely of the

casing from side to side thereof. Fixed within the casing is a guide member 16 that is spaced between the ends of the casing and engages one side wall of the latter, a space being left between the member 16 and the other side wall of the casing to accommodate the arm of the block 14, through which the shackle passes. This member 16 is formed with a slot 17 that extends transversely of the casing leaving a space between the two for insertion of the key, the casing having a suitable aperture 18 in its side wall for insertion of the key.

The member 16 is formed with apertures 20 which extend completely therethrough longitudinally of the casing. Projecting into these apertures 20 are the plunger pins 21 fixed to the block 14. A spring 23, located in the rear end of the casing bears, on the block 14 and holds the transverse arm thereof engaged with the rear face of the member 16. An additional plunger pin 25 is fixed in the block 14 and projects through an aperture in the member 16 into an angular recess 26 at one end of the latter. This pin is adapted to be engaged, when the lock is closed, by a pair of leaves 30 that are pivoted on the projecting end of the member 16 to swing parallel to the face of the latter and which project on opposite sides of the pin 25 when the lock is open. These leaves are urged toward one another by means of a wire spring 31 that is engaged at its ends with the respective leaves.

The shank of the shackle 13 is normally held against longitudinal movement with respect to the block 14, but is rotatable therein to allow of the beak of the shackle being swung to one side to be free of the casing. As here shown a transverse pin 34 in the shackle shank projects across one end of the block while the other inner end of the shackle shank is formed on one side with a flat-bottomed transverse groove 35 in which engages the free end of a finger 36 that is pivoted on a stud 37 fixed to the block 14 and adapted to swing transversely of the shackle shank, a spring 38 urging the finger into the groove 35. The engagement of the side of the finger 36 with the bottom of the groove 35 acts to yieldingly hold the shackle in position with its beak in registry with the aperture 12 in the casing, while permitting swinging of the shackle. A stop 40 on the block 14 limits movement of the finger 36 under the influence of the

10. When the padlock is closed, as in Figs. 4 and 5, the shackle is pushed inward and the leaves 30 extend across the end of the pin 25 and prevent the shackle moving outward. To release the lock the key is inserted in the opening 18 and its tapered forward end engages between the leaves 30 and spreads the same apart, freeing the pin 25. When the key reaches its extreme inward position the pins 21 register with the apertures 52 in the key and the shackle is then freed and is pushed outward by the spring 23, the key being locked in the casing. In closing the lock the shackle is simply pushed inward until the pins 21 are to the rear of the slot 17 when the leaves 30 swing over the end of the pin 25 and hold the parts in this position. The key may then be withdrawn. If it is desired to withdraw the key with the lock open the shackle is swung through an arc of one-hundred and eighty degrees and then pulled outwardly until its inner end passes the finger 36. The shackle is then pushed inwardly, bearing on the finger 36 and causing the block 14 to be moved to free the key. When the shackle is swung back to its original position with its beak in registry with the opening 12 and pushed inward the finger 36 is pushed to one side by the beveled end 42 of the shackle shank.

40. While I have shown and described a preferred embodiment of my improved padlock it is to be understood that I do not limit myself to the precise construction herein disclosed, and the right is reserved to the 45 use of keys with any number of apertures and to all changes and modifications coming within the scope of the invention as defined in the appended claims.

Having thus described my invention, 50 what I claim as new and desire to protect by Letters Patent of the United States is as follows:—

1. A padlock comprising a casing, a block 55 slidable longitudinally in said casing, a shackle mounted in said block for rotary movement, a plunger pin fixed to said block, an apertured guide member in said casing through which said pin projects, a spring urging said shackle to unlocked position, and a device adapted for release by a key 60 engaging over the end of said pin to hold the shackle in locked position, said device be-

and a device adapted for release by a key 75 engaging over the end of said pin to hold the shackle in locked position, said device being in the form of a leaf hinged to the said guide member, and a spring urging said leaf to position engaging over the end of the said pin.

3. A padlock comprising a casing, a block 80 slidable longitudinally in said casing, a shackle mounted on said block for rotary movement, a plurality of plunger pins fixed to said block and extending longitudinally of the casing, a guide element in the casing having longitudinal apertures to receive the 85 said pins and a transverse slot for insertion of a key, and a pair of leaves pivoted on said guide element and normally projecting across the end of one of said pins to retain the shackle locked.

4. A padlock comprising a casing, a block 90 slidable longitudinally in said casing, a shackle mounted on said block for rotary movement, a plurality of plunger pins fixed to said block and extending longitudinally 95 of the casing, a guide element in the casing having longitudinal apertures to receive the said pins and a transverse slot for insertion of a key, and a pair of leaves pivoted on said guide elements to retain the shackle 100 locked, and a key having a pointed end adapted for insertion between the said leaves to free the latter from the said pin.

5. A padlock comprising a casing, a block 105 slidable longitudinally in said casing, a shackle mounted on said block for rotary movement, a plurality of plunger pins fixed to said block and extending longitudinally 110 of the casing, a guide element in the casing having longitudinal apertures to receive the said pins and a transverse slot for insertion of a key, and a pair of leaves pivoted on said guide elements to retain the shackle 115 locked, and a key having a pointed end adapted for insertion between the said leaves to free the latter from the said pin, said key having a number of apertures 120 therein which register with the other plunger pins when the key is fully inserted in the lock.

In testimony whereof I have affixed my signature.

JOSEPH MATALONI,
